In Great Britain July 27, 1946

8 Claims. (Cl. 273—101)

1

Amongst the many different kinds of amusement machines or devices for use at fair grounds and other public similar places of entertainment, it has been proposed to provide a machine or device which comprises a manually-operated ejector for propelling a coin or other missile into the mouth of a chute which is adapted to direct the missile to a moving member, the delivery outlet from the chute being arranged vertically above the path of the said moving member.

In accordance with one such proposal, the moving member comprises a rotatable drum which is divided into a plurality of radial compartments, the mouths of which are arranged to pass in succession vertically below the said chute outlet.

In practice, it is customary to divide the plurality of radial compartments into several categories or groups, to space the compartments in each group around the area of the drum, and to arrange that each of the several categories or groups shall represent a different prize-earning value when the missile projected by the ejector is directed into one of the compartments of a category or group.

Any person (hereinafter referred to as "the competitor") operating the ejector would, naturally, expect the conditions to be such that it is more difficult to direct a missile into a compartment included in a prize-earning category or group, than into a non-prize-earning compartment, and that the higher the prize-earning capacity of any compartment, the more difficult it is to direct a missile into that compartment.

Therefore, one object of the present invention is to provide a machine or device of the kind referred to above, wherein the possibility of the competitor directing a missile into a prize-earning compartment is reduced automatically as a compartment of any of the prize-earning categories passes below the chute.

Another object of the invention is to reduce automatically, and in proportion to the value of the prize to be won, the possibility of the competitor directing a missile into a compartment included in a prize-earning category or group.

A further object of the invention is to provide simple and efficient means or mechanism for automatically reducing the possibility of a coin being directed into a prize-earning compartment, and still another object is to provide simple and efficient means or mechanism whereby the said reduction is proportional to the prize-earning capacity of the compartment passing below the chute.

2

These and other objects of the invention will be apparent from the specific embodiments of the invention illustrated diagrammatically in the accompanying drawings, in which—

5 Figure 1 is a front perspective view of an amusement machine or device of the kind hereinbefore referred to.

Figure 2 is a rear elevation of the device shown in Figure 1 and illustrating one convenient form 10 of carrying out the present invention.

Figure 3 is a sectional elevation of a part of the device, showing the chute control means in operation.

15 Figure 4 is a rear view, similar to Figure 2, of a modified or alternative and simpler form of carrying out the invention.

Figure 5 is a sectional elevation along the line a—a, Figure 4.

20 Figure 6 is a plan view of a detail of construction.

The amusement machine or device shown in Figures 1 to 4, comprises a base 1 which is provided with a front shelf 2 on the top edge of which a manually operable ejector 3 is rigidly secured. The said ejector includes a platform 4 for receiving a missile, such as a coin or like disc, and an operating handle 5 for retracting and releasing a spring-loaded hammer (not shown) adapted to project the missile along the platform towards the rear of the machine. The base, shelf and ejector may be of any desired and suitable construction.

25 The rear of the machine is provided with the back-board 6 which is of hollow construction and is formed with an opening 7 in its front face and is provided, above the said opening, with an auxiliary missile-receiving aperture 8 having a cowl 8^a along its upper end and lateral edges for guiding missiles into and through the said auxiliary aperture.

30 Within the back-board, and visible through the opening 7, is a drum 9 which, in the machine illustrated, is divided into twenty-four identical radial compartments, 10, 11, 12, and 13, each having its missile-receiving mouth opening at the periphery of the drum.

35 The said drum is rotatable about a spindle 14 carried at its opposite ends in a bracket 15 extending across the front of the aperture 7 and another bracket 16 extending across and behind the back-board 6. A chute 17 is provided within the back-board between the drum 9 and the auxiliary aperture 8, the mouth or inlet end of the said chute being of such dimensions that it extends from the front to the back walls of the

back-board and at least from side to side of the auxiliary opening 8. The chute tapers to its delivery end which is located vertically above the spindle 14 and preferably is of a cross-sectional area not less than the area of the mouth of any one of the identical compartments 10-13.

The rear wall of the back-board is formed with a circular aperture 18 through which the drum 9 projects and a worm wheel 19 is rigidly and concentrically secured to the rear face of the said drum. A worm 20 driven by an electric motor 21, meshes with the said worm wheel and is adapted to drive the latter around the spindle 14, at a comparatively slow speed.

Three concentric cam rings 22, 23, 24, are mounted upon the rear face of the said worm wheel, each cam being provided with a plurality of spaced cam noses 22^a, 23^a and 24^a respectively, the total number of cam noses being equal to the number of prize-earning compartments, the noses on each ring being equal to the number of compartments included in a complementary category or group of a specified prize-earning capacity, and the noses on each of the three rings being of different depth.

Rollers 25, 26 and 27, are rotatably mounted upon the lower ends of rocker arms 28, 29 and 30, respectively, all the arms being journalled intermediate their ends upon a common rod 31 carried between a pair of brackets 32 fixed upon the rear of the back-board, and each of the said arms being loaded by a complementary spring 37 so that its roller-carrying lower end is urged towards the worm wheel 19. Thus the rollers 25, 26 and 27, are held in continuous contact with the cam rings 22, 23 and 24 respectively.

At their upper ends, the rocker arms 28, 29 and 30 are coupled respectively to obturators or shutters 33, 34, and 35, the said shutters being arranged to slide in separate planes at right angles to the backboard and being carried by a slotted bracket 36 fixed to the rear face of the said backboard.

In the machine or device shown in the drawings, the twenty-four compartments are divided into four categories or groups; the compartments 10 are of the highest prize-earning capacity and are three in number, there being three corresponding deep cam noses 22^a on the cam ring 22.

The compartments 11 are of an intermediate prize-earning capacity and are four in number, four corresponding cam noses 23^a of intermediate depth, on the cam ring 23. The compartments 12 are of the lowest prize-earning capacity and are six in number, six corresponding shallow cam noses 24^a being provided on the cam ring 24. The remaining eleven compartments 13 have no prize-earning capacity and, therefore, if a missile enters any one of these losing compartments 13, the competitor receives no prize or fails to add to his score.

As the drum 9 is rotated by the motor 21, worm 20 and worm wheel 19, the mouths of the compartments 10-13 are moved in succession below the outlet end of the chute 17. Also, as each of the cams 22^a, 23^a and 24^a approach and travel below their complementary rollers 25, 26 and 27, the latter are forced away from the worm-wheel, causing the rocker arms 28, 29 and 30, to swing about the rod 31, against the action of the springs 37, in the direction which causes the shutters 33, 34 and 35 to move across the throat of the said chute; as the cam noses ride from under the rollers the bracket arms and spring return to their initial positions.

Since the cam noses 22^a are of the greatest depth, the shutter 33 will be moved to the greatest distance across the throat of the chute each time its rocker arm is displaced by one of the three noses 22^a; also, since the cam noses 24^a are of the least depth, it follows that the shutter will be moved to the smallest distance across the throat each time it is actuated under the control of one of the six cam noses 24^a.

10 The cam noses 22^a, 23^a and 24^a, are arranged around their respective cam rings so that only one of the shutters can be moved to its limit across the throat of the chute 17 at any one time, and so that each shutter is at the limit of its throat restricting movement whilst the mouth of the complementary compartment is disposed wholly below the outlet from the said chute.

15 In the application of the invention shown in the drawings, the arrangement and length of the cam noses is such that each shutter commences its throat restricting movement as the complementary compartment mouth begins to move below the chute outlet, reaches the limit of the said movement when half the mouth area is disposed below the said outlet, and commences its return movement when half the mouth has passed beyond the outlet.

20 Consequently, when a compartment 10 of the highest prize-earning category or group is disposed below the chute outlet, the throat of the chute is restricted to a maximum degree by the shutter 33 so that the effective area remaining for the passage of a missile, and the possibility of the missile entering the said compartment 10, 30 is reduced to a minimum; similarly, when a compartment 11 of the intermediate prize-earning category or group is disposed below the chute outlet, the throat is restricted to an intermediate extent by the shutter 34, when a compartment 12 of the lowest prize-earning capacity is so disposed, the throat is restricted to the smallest extent by the shutter 35, and when a non-prize-earning compartment 13 is located wholly below and in register with the said outlet, there is no restriction of the throat at all.

25 In Figure 3, the roller 27 is shown on the crown of one of the six cam-noses 24^a so that the shutter 35 is at the limit of its throat-restricting movement; the roller 25 is commencing its ride up one edge of a cam 22^a so that the shutter 33 has commenced its throat-restricting movement, and the roller 26 is clear of the cams 23^a so that the shutter 34 is wholly withdrawn from the chute. The maximum throat-restricting positions of the said shutters 33 and 34 are shown in dotted lines.

30 When it is deemed necessary to restrict the throat of the chute 17 only when a compartment of the maximum prize-earning capacity is passing below the outlet from the chute, or when only one category or group of prize-earning compartments is provided, the machine or device may be simplified in the manner shown in Figures 4 and 5. The machine or device shown in these drawings comprises only one obturator or shutter 40, which is displaceable by a rocker arm 41 loaded by a spring 42 and provided at its lower end with a roller 43 spring urged against the back of the worm wheel 19. The cam-noses 44 for displacing the roller, rocker arm and shutter against spring action, are assembled direct to the said wheel 19 instead of being formed upon a cam ring as in Figures 1 to 3.

35 Instead of arranging for the shutters 33-35 of Figures 1 to 3 to be moved through different

distances across the throat of the chute, in the manner described above, the arrangement may be such that the shutters are displaced through equal distances. In such circumstances as shown in Figure 6, the variation in the restriction of the chute throat according to the prize-earning capacity of the compartment passing below the chute outlet, may be brought about by providing a slot or recess in the leading edge of each shutter, the recess 50 in the shutter 33 10 being of the smallest area, the recess 51 in the shutter 34 being of an intermediate area, and the recess 52 in the shutter 35 being of the greatest area. The recessing of the shutter edges has the advantage that it is impossible wholly 15 to close the throat even if, due to some fault, end adjustment or wear, a shutter is taken into abutting contact with the front wall of the chute.

When a competitor fires a missile from the 20 injector 3, the said missile is directed by the inclination of the platform 4, into and through the auxiliary aperture 8 and, if driven with sufficient speed, against a fabric or like back-cloth or baffle 45 (see Figure 5) which is suspended from the top of the back-board in spaced relationship to the rear wall of the latter, prevents or reduces the possibility of the missile rebounding through the said aperture, and also reduces the noise created if a coin or other metal or hard 25 missile is fired.

After striking the said baffle, the missile falls through the mouth of the chute and down the latter. Provided the throat of the chute is not restricted by any of the shutters, the missile 30 falls straight into a compartment of the drum 9; however, if the throat is restricted, the missile may fall and temporarily come to rest upon the throat-restricting shutter and, therefore, its 35 passage down the chute is likely to be delayed for sufficient time to enable a compartment of one prize-earning capacity to pass from under the chute outlet and be replaced by a non-prize-earning compartment, or by a prize-earning compartment of a lower prize-earning category 40 or group.

As and when a missile falls into a prize-earning compartment, it closes an electric circuit and causes one of the lamps 46, 47 or 48 (see Figure 1) to be illuminated thereby giving to the 50 competitor a readily-visible indication that a prize has been won and also, according to which of the three lamps is illuminated, the value of such prize. (This prize-indicating means forms no part of the present invention and, therefore, 55 is not illustrated in detail in the accompanying drawings.)

The front face of the drum is divided into twenty-four zones of equal area to and coincident with, the compartments (see Figure 1), 60 each zone being colored to indicate its prize-earning capacity. Thus, the competitor is able to select the time of firing the ejector with the object of directing a missile into a pre-selected compartment.

I have illustrated and described three alternative applications of my invention, but it will be understood that the invention may be otherwise applied or practised within the scope of the following claims. For example, the drum 9 may be adjustable lengthwise of the spindle 14 by mounting it upon cone bearings (in the same way as a bicycle wheel is mounted upon its spindle) so that the mouths of the compartments 65 10-13 may be brought into register with the

outlet from the chute 17; the cam rings 22, 23 and 24 of Figures 2 and 3 may be adjustable circumferentially upon the back of the worm wheel 19, or the thirteen cams 22a-24a shown in the said Figures 2 and 3 may be mounted individually and, if desired, in an adjustable manner directly on the said wheel instead of being formed upon cam rings; or again, the said cams 22a-24a may be arranged in one ring only so that they are adapted to displace only a single shutter through varying throat-restricting distances. Again, any desired number of radial compartments may be formed in the drum and these compartments may be divided into any desired number of prize-earning categories or groups provided that a similar number of groups of cams of different depths are also provided. If desired, alternative means for restricting the effective area of the chute throat to varying degrees may be adopted in place of the slideable shutters. Obviously, if desired, two or more drums, and the auxiliary components required therefor, may be arranged side-by-side in a single machine or device so that several competitors may be firing missiles at the time.

The term "prize-earning" does not necessarily imply that the competitor shall be entitled to a prize if the projected missile enters one of the compartments 10-12, it includes such conditions as a certain score being credited to the competitor as a result of a missile entering one of the prize-earning compartments and a prize being awarded to the competitor who succeeds in reaching the highest score after firing a preselected number of missiles.

Having described my invention what I claim and desire to secure by Letters Patent is:

1. An amusement device comprising a drum journaled at its center about a horizontal axis and divided internally thereof into a plurality of radial compartments opening around the drum periphery, a motor for rotating the drum, a missile-receiving chute arranged above the drum extending into a throat-shaped delivery outlet the latter being disposed vertically above and adjacent the periphery of the drum, at least one annular series of cams on one side of said drum, rollers held in contact with said cam carrying drum and shutters actuated by said rollers for periodically restricting said throat-shaped delivery outlet through which a missile may pass towards said drum.

2. An amusement device comprising a drum journaled at its center about a horizontal axis and divided internally thereof into a plurality of radial compartments opening around the drum periphery, a motor for rotating the drum, a missile-receiving chute arranged above the drum extending into a throat-shaped delivery outlet the latter being disposed vertically above and adjacent the periphery of the drum, at least one annular series of cams on one side of said drum, rollers held in resilient contact with said cam carrying drum and shutters actuated by 65 said rollers for periodically restricting said throat-shaped delivery outlet through which a missile may pass towards said drum.

3. An amusement device comprising a drum journaled at its center about a horizontal axis and divided internally thereof into a plurality of radial compartments opening around the drum periphery, said compartments being divided into a plurality of groups each of a different prize-earning capacity, a motor for rotating the drum, 70 a missile-receiving chute arranged above the

drum extending into a throat-shaped delivery outlet the latter being disposed vertically above and adjacent the periphery of the drum, at least one annular series of cams on one side of said drum, rollers held in contact with said cam carrying drum and shutters actuated by said rollers for periodically restricting said throat-shaped delivery outlet through which a missile may pass towards said drum, the degree of restriction being dependent upon and increasing with the prize-earning capacity of the compartment passing below the said delivery outlet.

4. An amusement device comprising a drum journaled at its center about a horizontal axis and divided internally thereof into a plurality of radial compartments opening around the drum periphery, the said compartments being divided into a plurality of groups each of a different prize-earning capacity, a motor for rotating the drum, a missile-receiving chute arranged wholly above the drum with its delivery outlet vertically above and adjacent the drum periphery, at least one annular series of cams of varying depths on one side of the drum, a spring-loaded rocker arm associated with each of the said series, rollers held at the one of said arms in contact with said cams so as to be rocked by the same and shutters attached to the other end of said rocker arm actuated by said rollers for periodically restricting the effective cross area of said delivery outlet through which a missile can pass towards the drum, the degree of restriction being dependent and increasing with the prize-earning capacity of the compartment passing below the said delivery outlet.

5. An amusement device comprising a drum journaled at its center about a horizontal axis and divided internally thereof into a plurality of radial compartments opening around the drum periphery, the said compartments being divided into a plurality of groups each of a different prize-earning capacity, a motor for rotating the drum, a missile-receiving chute arranged wholly above the drum extending into a throat-shaped delivery chute the latter being disposed vertically above and adjacent the drum periphery, a plurality of concentric and annular series of cams, equal in number to the prize-earning groups of compartments on one side of the said drum, the cams in each series being of uniform depth and of a depth different from the depth of the cams in the other series, rollers held in contact with the said series of cams carrying drums and shutters actuated by said rollers for periodically restricting said throat-shaped delivery chute through which a missile may pass towards the drum, the degree of restriction being dependent and increasing with the prize-earning capacity of the compartment passing below the said delivery chute.

6. An amusement device comprising a drum journaled at its centre about a horizontal axis and divided internally thereof into a plurality of

radial compartments opening around the drum periphery, a motor for rotating the drum, a missile-receiving chute arranged above the drum extending into a throat-shaped delivery outlet the latter being disposed vertically above and adjacent the periphery of the drum, at least one annular series of cams on one side of the said drum, a shutter associated with each series of cams and a rocker arm operable by said cams for displacing the said shutter inwardly and outwardly of said throat-shaped delivery outlet.

7. An amusement device comprising a drum journaled at its center about a horizontal axis and divided internally thereof into a plurality of radial compartments opening around the drum periphery, a motor for rotating the drum, a missile-receiving chute arranged wholly above the drum extending into a throat-shaped delivery outlet the latter being disposed vertically above and adjacent the periphery of the drum, a plurality of annular and concentric series of cams on one side of said drum, a separate shutter associated with each one of the said cam series and a rocker arm operable by a corresponding cam series for displacing the said shutter inwardly and outwardly of said throat-shaped delivery outlet, the arrangement being such that not more than one shutter is disposed at the inward end of its stroke at any one time.

8. An amusement device comprising a drum journaled at its center about a horizontal axis and divided internally thereof into a plurality of radial compartments opening around the drum periphery, a motor for rotating the drum, a missile-receiving chute arranged wholly above the drum extending into a throat-shaped outlet the latter being disposed vertically above and adjacent the periphery of the drum, a plurality of annular and concentric series of similar cams on one side of said drum, a separate shutter associated with each one of the said cam series, each of the said shutters having a recess in one edge, said recess in each of the said shutters having a different area from the recesses in the other shutters and a separate rocker arm operable by each cam series and coupled to a shutter for displacing the same, recessed-edge foremost, inwardly and outwardly of said throat-shaped delivery outlet, the arrangement being such that not more than one shutter is disposed at the inward end of its stroke at any one time.

FRANCIS J. PEACOCK.
